UNITED STATES PATENT OFFICE.

LOUIS E. BALTZLEY, OF GLEN RIDGE, NEW JERSEY.

BINDER.

Application filed August 13, 1921. Serial No. 491,944.

To all whom it may concern:

Be it known that I, LOUIS EDWIN BALTZLEY, a citizen of the United States, and a resident of Glen Ridge, county of Essex, 5 and State of New Jersey, have invented certain new and useful Improvements in Binders, of which the following is a specification.

My present invention is a temporary 10 binder on the order of that disclosed in my Patent No. 1,388,140, August 16, 1921, the particular objects in this case being to provide a binder of that type which will be quick-opening and self-closing in its operation.

In the accomplishment of these and other 20 objects I make use of certain novel features of construction, combination and relation of parts, as will appear in the course of the following specification, which is to be read in conjunction with the drawing accompanying and forming part of the same.

As this drawing is intended primarily for 25 purposes of disclosures, it will be understood that the structure may be modified in various respects without departure from the true spirit and scope of the invention as hereinafter defined and claimed.

Figure 1 in the drawing referred to is a 30 side elevation of the binder in its normal closed condition.

Figure 2 is a cross sectional view of the same, showing it held in the open relation.

Figure 3 is a back view of the binder in 35 its closed condition.

Figure 4 illustrates a form of lever mechanism for operating the jaws.

Figure 5 is a rear view showing a modified 40 form of spring.

Figure 6 is a broken detail view of a binding 45 screw construction for securing the jaws in adjusted relation, and Figure 7 is a similar view of a cam lever form of securing means.

The cooperating jaw members 5 and 6 of 50 the binder are connected in my invention by having oversliding back portions 7 and 8 curved on substantially concentric arcs drawn from a center 9 which is located at a point to the rear of and outside the binder.

As will be clear from Figures 1 and 2 this 55 results in the jaw members having an opening movement about a center which is extraneous to the binder and hence an extremely wide-angle opening is accomplished within a binder of only moderate propor-

tions. In other words, this construction embodies the wide-opening attribute with that of compactness.

The curved back portions are confined to 60 the sliding movements described by suitable guide means, such as the curved lips 10 at the ends of one of the back portions which are arched over the edges of the companion back portion.

The jaws are operated in the present disclosure by the handles 11 and 12 projecting rearwardly from the ends of the back portions, the handle of the inner back portion operating through a slot 13 provided in the outer back portion. The expansion spring 14 interposed and held between these handles provides the force for normally holding the jaws in their closed relation. Upon pinching the handles together against the 70 tension of this spring it will be seen that the curved elements will be caused to slide one over the other, so as to spread the jaws, as shown in Figure 2, and that on the release of this pinching force the spring will 75 instantly close the jaws. The construction thus provides a quick acting easily manipulated clamp, which, if desired, can be handled entirely by the operating handles. These handles are in part received within 80 the cavity at the back of the binder and so are protected to a material extent against accidental operation.

In Figure 4 I have shown how the handles may be extended to form crossed levers 90 11' and 12', these levers being shown as pivotally connected at the point of crossing at 9', which point corresponds to the center from which the arcs of the backs are described. It will be obvious that by thus 95 lengthening the handles, any desired lever- age can be obtained.

In Figure 5 I have shown how a bowed 100 spring 15 of wire or the like may be substituted for the coiled spring first illustrated. This bowed spring is shown as made of a single piece of spring wire having an offset 105 16 in the center of its arch engaged beneath the handle 11 of the inner back member and as having its ends slidingly engaged under lips or hooks 17 struck from the outer back member.

If desired, the closing spring may be 110 omitted and the jaws be simply adjusted by hand and then fastened by suitable securing means in their adjusted relation.

Figure 6 illustrates a form of securing

means suitable to this purpose and consisting of a thumb nut 18 on the screw stud 19 which is fixed to the inner back member and projects through a slot 20 in the outer back member. The inner end of this thumb nut is preferably rounded to bind against the concave face of the outer back member. Upon loosening the thumb nut it will be apparent that the jaws are free for adjustment in either opening or closing directions and it will be seen that when the proper adjustment is obtained, the jaws are quickly and firmly secured by simply tightening the thumb nut.

15 The securing means shown in Figure 7 is in the form of a lever 21 pivoted at 22 on the stud 19 and having cam portions 23 for binding engagement with a washer 24 bearing against the outer back member. It will be seen that by turning this lever one way or the other, the back members may be released or secured in any desired adjustment.

20 Where handles such as I have first illustrated are provided for operating the binder jaws, these are terminated short of the point

where the pressure would be applied to opposite sides of the center (9) about which the jaws travel, as I have indicated diagrammatically in Figure 1, so that the operating force will be effective to actually shift the jaws and not simply exert a binding force thereon.

What I claim is:

1. A binder comprising cooperating jaw members slidably connected at the rear by concentrically curved oversliding back portions arranged with the concave faces thereof to the rear of the binder and one having integral confining lips arched over the curved surfaces of the other to hold the curved back portions close together in sliding relation.

2. The structure of claim 1 with separate and independent handles projecting free of each other from the rear of the curved back members and a spring acting on the handle of one of the back members and bearing against a part of the other back member.

In witness whereof, I have hereunto set my hand this 10th day of August, 1921.

LOUIS E. BALTZLEY.
